UNITED STATES PATENT OFFICE.

WILLIAM T. LEARMONT, OF PORTAGE, WISCONSIN.

JACK.

1,347,862.

Specification of Letters Patent. Patented July 27, 1920.

Application filed November 28, 1919. Serial No. 341,106.

To all whom it may concern:

Be it known that I, WILLIAM THOMAS LEARMONT, a citizen of the United States, and resident of Portage, in the county of 5 Columbia and State of Wisconsin, have invented new and useful Improvements in Jacks, of which the following is a description, reference being had to the accompanying drawings, which are a part of this 10 specification.

The invention relates to lifting jacks and more particularly to one for removing racks from or placing them on wagon bodies.

The object of this invention is to provide 15 a jack which will accommodate itself to the tilting movements of the rack frame during its removal from or disposition on the wagon body. To accomplish this purpose the jack is pivotally supported at its upper 20 end in a supporting frame and as the end of the rack frame swings about one of its ends the jack swings also to accommodate this swinging movement of the rack.

The invention further consists in the 25 novel arrangement and combination of parts hereinafter described and more particularly defined by claims at the conclusion hereof.

In the drawings: Figure 1 is a side elevational view of the device embodying the invention; Fig. 2 is an end view of the device, parts being broken away and parts being shown in section; Fig. 3 is a section taken on the line 3—3 of Fig. 2.

The supporting frame consists of a pair 30 of metal frame members 4 having vertically disposed portions 5 and diverging lower portions 6. These members are secured together in spaced relation by U-shaped bars 7 and 8 connected to the upper and lower 40 ends of the portions 5. The lower ends of the portions 6 are provided with spaced holes 6' so that foot members 9 may be adjustably secured thereto by bolts 10, said members 9 having angle iron bases 11 secured to bars 12 and braces 13.

The frame members 4 have bearings 14 in their upper ends receiving trunnions 15 carried by a swinging jack frame 16. This frame is of open rectangular construction 50 having a rack face 17 in one side thereof and aligned guide openings 18 in the ends thereof.

A lifting bar 19 is slidably mounted in the guide openings 18 and is provided with 55 a rack face 20 facing the rack 17. A pinion 21 meshes with both of the racks 20 and 17

and is keyed to a shaft 22 provided with a crank handle 23 so that as the shaft 22 is turned the pinion 21 moves along the rack 17 and the bar 19 is moved by the pinion. 60 This action causes the bar 19 to move twice the distance it would travel were it operated by a pinion having a relatively fixed position. To prevent accidental descent of the bar 19 while it is being lifted, or to hold it 65 in adjusted position, a pawl 24 pivotally mounted on the frame 16 engages with the teeth. For lowering the bar 19 this pawl may be swung out of engagement with the 70 rack.

Guide plates 25 mounted on the shaft 22 serve to hold the pinion in line with the frame 16 and bar 19.

As shown in Fig. 1, the rack frame 16, as the rack bar 19 is raised or lowered with 75 respect thereto, is free to tilt in the supporting frame so that the end of a rack frame member 26 may be raised or lowered without changing the position of the supporting frame. In case it is desired to move 80 a hay rack from the body of a wagon, the operator first raises the rear end, the hay rack swinging on its front end as it is raised and the upper end of the rack bar being free to swing inwardly. The rear end is 85 raised to a position where it may rest upon a stationary support and then the jack is moved to the front of the wagon and the front end of the hay rack is then raised upon a stationary support, the swinging of 90 the rack bar again assisting in this operation.

It will be noted that the transverse portions of the members 8 and 7 will serve to limit the tilting movement of the jack 95 frame.

I desire it to be understood that this invention is not limited to any specific form or arrangement of parts except in so far as such limitations are specified in the claims. 100

What I claim as new and desire to secure by Letters Patent is:

1. In a lifting jack, the combination of a supporting frame, a jack frame carrying trunnions vertically swingingly mounted on the upper portion of said supporting frame and provided with a rack, a lifting bar slidably mounted in said jack frame and provided with a rack, a pinion meshing with both racks, and means swinging with the 110 jack frame to turn said pinion.

2. In a lifting jack, the combination of a

- supporting frame having bearings near its upper end and frame members above and below said bearings to limit the movement of the jack frame, a jack frame carrying 5 trunnions vertically swingingly mounted in said bearings, a lifting bar slidably mounted in said jack frame, and means carried by the jack frame for raising and lowering said lifting bar.
- 10 3. In a lifting jack, the combination of a supporting frame, an open rectangular jack frame pivotally mounted intermediate its end on the upper portion of said supporting frame, one of the sides of said jack 15 frame being provided with a rack and the

ends of said jack frame having aligned openings, a rack bar slidably mounted in said openings and provided with a rack facing the first named rack, a pinion meshing with both racks, a crank shaft secured to said pinion, and a retaining pawl pivotally supported on said jack frame and engageable with the rack on the lifting bar.

In testimony whereof I affix my signature in presence of two witnesses.

WILLIAM T. LEARMONT.
